UNITED STATES PATENT OFFICE.

HIRAM K. RITTER, OF READING, PENNSYLVANIA.

CLAMP FOR RAILS.

SPECIFICATION forming part of Letters Patent No. 604,792, dated May 31, 1898.

Application filed October 27, 1897. Serial No. 656,603. (No model.)

To all whom it may concern:

Be it known that I, HIRAM K. RITTER, a citizen of the United States, residing at Reading, in the county of Berks and State of Pennsylvania, have invented a certain new and useful Improvement in Clamps for Rails and the Like, of which the following is a specification.

My invention relates to a new and useful improvement in clamps for the securement of railway-rails to the cross-ties when the latter are of metal and also for the securement of structure-irons for building purposes.

With these ends in view this invention consists in the details of construction and combination of elements hereinafter set forth, and then specifically designated by the claims.

In order that those skilled in the art to which this invention appertains may understand how to make and use the same, the construction and operation will now be described in detail, referring to the accompanying drawings, forming a part of this specification, in which—

Figure 1 is a perspective of a portion of a railway-rail, showing the ends of two metal cross-ties, illustrating the application of my improvement for securing the rail in place; Fig. 2, a side view of the rail, showing the cross-tie in section; Fig. 3, a cross-section of the rail, showing the cross-tie in elevation and the clamps in position; Fig. 4, a detail perspective of one of the clamps, and Fig. 5 a perspective illustrating the application of my improvement to building purposes.

In carrying out my invention as here illustrated, A represents a railway-rail resting upon the cross-ties B, and this rail is preferably notched at points which fall upon the ties, as indicated at C, while the ties are notched, as indicated at D.

The clamps are made of metal plates cut and bent, as shown in Fig. 4, so as to produce the body E, which is adapted to pass within the notch C and lie upon the upper surface of the flange F of the rail, and this clamp-plate also has formed therewith a hook G, adapted to enter into engagement with the notch D and also extend beneath the flange H of the tie. In the formation of the clamp-plate a tongue I is produced by a slit severing it from the body E, and in practice this tongue is turned

downward and forced beneath the flange F of the rail, as clearly shown in Fig. 3. From this it will be seen that when a clamp-plate has been placed upon each side of the rail and engaged therewith and with the tie the said rail will be held against either longitudinal or sidewise movement, so that without the use of bolts or spikes a railway-track may be laid which will be as rigid as when laid by the old method.

In the application of my improvement to building purposes, as illustrated in Fig. 5, the beam J may be secured in place upon the beam K by the use of the clamps L, of the same construction as that above set forth; but there is no need for notching either of the beams, as the clamp-plates will take sufficient hold thereon to prevent accidental displacement thereof, and the advantage of this arrangement is that when the position of any of the beams is desired to be changed the same may be accomplished without drilling holes in the flanges of the beams, which often requires much laborious work, whereas by my improvement the beams may be secured in place without having to consider the exact point at which they cross.

Of course I do not wish to be limited to the exact arrangement here shown, as the details may be slightly varied without departing from the spirit of my invention.

Having thus fully described my invention, what I claim as new and useful is—

1. A clamp for securing rails, &c., in place consisting of a body, slit transversely producing two parts one of which is adapted to be forced beneath the flange of one member and the other part to overlap said flange, and a tongue formed on said body to engage the flange of the other member, substantially as shown and described.

2. In combination, a railway-rail having notches therein, cross-ties also having notches therein, a clamp-plate having a body for engagement with a flange of the rail and a notch therein, a hook formed upon said clamp adapted for engagement with the flange of the tie and a notch therein, and a tongue so arranged as to be forced beneath the flange of the rail, as specified.

3. The herein-described combination of two

beams crossing each other, a clamp-plate consisting of a body adapted to overlap the flange of one of said beams, a tongue for passing beneath said flange, and a hook projecting at right angles to the tongue and body adapted to engage with a flange of the other beam, as shown and described.

In testimony whereof I have hereunto affixed my signature in the presence of two subscribing witnesses.

HIRAM K. RITTER.
